Term of patent 14 years

(Cl. D14—30)

Fig. 1

Fig. 2

Figure 1 is a side elevational view of my novel design
for a tire trim; and

Figure 2 is a fragmentary sectional perspective view
of the tire trim.

The dotted lines in the figures showing the conventional tire rim and tire are for illustrative purposes only.

I claim:

The ornamental design for a tire trim, substantially
as shown and described.
